[57] CLAIM

The ornamental design for a cushion for the back of a chair or the like, as shown and described.

DESCRIPTION

FIG. 1 is a perspective view of a cushion for the back of a chair or the like showing my new design, the broken-line depiction of a portion of a chair being for illustrative purposes only and forming no part of the claimed design;

FIG. 2 is a front elevational view thereof;

FIG. 3 is a left side elevational view thereof, the right side being a mirror image of that shown;

FIG. 4 is a top plan view thereof;

FIG. 5 is a bottom plan view thereof, and

FIG. 6 is a rear elevational view thereof.

FIG. 3

FIG. 2

FIG. 4

FIG. 5

FIG. 6
